UNITED STATES PATENT OFFICE.

YVES PAUL GASTON LE PRIEUR, OF PARIS, FRANCE, ASSIGNOR TO SOCIÉTÉ ANONYME
LA PRÉCISION MODERNE, OF PARIS, FRANCE.

SIGHT FOR MACHINE GUNS FOR ANTI AIRCRAFT FIRING.

Application filed May 4, 1926, Serial No. 106,703 and in France May 16, 1925.

The back sight correction (Fig. 1) is calculated by the well-known vertical back-sight method. Suppose ab is the barrel of a fire-arm levelled at a target disposed in the horizontal plane (site zero). The line of sight passes through a sight b disposed in front of the vertical line ac . If it is desired to fire at a target disposed at the same distance as the first target considered but at a point 10 the angle of site of which is s , it can easily be calculated and experience shows that it is sufficient to rotate the fire arm round s in order to bring its end in b' without changing the back sight ac , provided this back sight 15 remains vertical.

The mechanical apparatus according to my invention which embody these principles are especially intended for use with portable fire arms such as machine-guns. They must 20 therefore show at the same time the maximum simplicity and ease in handling as well as the maximum strength and also require the minimum effort from the gunners. They are constituted by a cylindrical casing kept 25 constantly vertical and wherein is disposed a cylindrical box which can rotate inside the said casing. The cylindrical box is traversed by a vertical rod which can move along a radius of the box while remaining parallel 30 to its original position. This rod is pivotally secured at one of its ends to an arm or a directing shaft pivotally secured to a horizontal shaft secured to the box, the said arm or directing shaft being disposed parallel to 35 the path followed by the aircraft. At its other extremity the aforementioned rod is pivoted to another rod bearing the aiming device and connected with a part of the fire-arm.

40 The cylindrical casing can be secured to the fire arm after the manner of a pendulum and the verticality of its axis can be provided by an arrangement comprising an articulated parallelogram secured to the support of the fire-arm.

In the apparatus according to the present invention the directing shaft can be directed parallel to the path followed by the aircraft whether this path is horizontal or not. But 50 when the path is not horizontal, if for instance the aircraft moves downward its speed increases; if it rises on the contrary its speed diminishes. An important feature of the devices built according to my present invention 55 consists in that a suitable speed correction is

automatically introduced when the directing shaft is rotated round its horizontal pivot.

In view of this, several arrangements have been devised which embody the following principle: a controlling part actuates directly a carriage the movement of which depends on the speed, whereas the socket which the vertical rod passing through the box engages, is secured to another carriage slidably mounted on the first carriage. This second carriage is adapted to be moved along with the first one when the controlling part is actuated, but it can also be moved independently with reference to the said first carriage; this independent movement being caused when the directing shaft is directed parallel to the inclined path followed by the aircraft.

Several forms of execution of a sight line according to my invention are shown by 75 way of example on appended drawings whereof:

Figs. 1 and 2 described hereinabove disclose the principle of the apparatus.

Figs. 3 to 10 relate to a first form of execution of an apparatus.

Fig. 3 is a general perspective view thereof.

Fig. 4 is a plan view.

Fig. 5 is a detail sectional view through the 85 cylindrical box.

Fig. 6 is a detail of Fig. 5 showing the arrangement of the two carriages slidably secured together, the outer carriage having been cut so as to allow the working of the 90 arrangement to be readily understood.

Fig. 7 is a sectional view similar to Fig. 5 of a modified form of the apparatus.

Fig. 8 is a detail sectional view of the modified form, perpendicular to the section 95 shown by Fig. 7.

Fig. 9 is a section similar to those of Figs. 5 and 7 of another modified form of execution and

Fig. 10 is a detail section perpendicular 100 to Fig. 9 of this last modified form.

Figs. 11 to 13 relate to the second form of execution embodying the formula (2).

Fig. 11 is a general outer view thereof.

Fig. 12 is an explanatory diagram and 105

Fig. 13 shows the detail of the different members of the sight line and of the calculating box.

Referring to Fig. 3, 1 is the machine gun around which is set the support 2 on which 110

the slider 3 secured to a block 4 is adapted to move parallel to the axis of the machine gun. A circular limb 5 (Fig. 5) is cast with the support 2 and serves to guide and to hold securely the cylindrical casing 6 which hangs after the manner of a pendulum. In order to keep the axis of the cylindrical casing constantly vertical, the latter is provided with a lug 7 pivotally secured to the connecting rod 8. The said connecting rod is on the other hand pivotally secured at a stationary point 9 to the support 10 of the machine gun. Thus an articulated parallelogram is obtained the four apices of which are the trunnion 11 of the machine gun, a point of the axis wherethrough the casing 6 is pivoted on to the support 2, the pivoting point of the lug 7 with the connecting rod 8 and the point 9. It can be noticed that by means of this articulated parallelogram, the whole of the sight line can be borne by the machine gun itself whereby the use of a special bearing frame is made unnecessary. Inside the casing 6 is disposed the cylindrical box 12 which can be raised or lowered with reference to the casing 6 and rotate with reference thereto. The crank 13 disposed on the support 2 allows simultaneously the slider 3 to be moved with reference to the support 2 and the box 12 to be raised or lowered with reference to the casing 6. To the box 12 is secured the socket 14 wherein the arm or directing shaft 16 is adapted to rotate round the horizontal axis 15 so as to be directed parallel to the path followed by the aircraft. To this shaft is pivotally secured the rod 17 which passes through the box 12 and bears at its top part a socket 18 supporting a swivel joint 19 which connects the rod 17 with the rod 20. This latter rod passes through a sleeve 21 bearing a luminous collimator 22 such as the "Chretien" collimator. The sleeve 21 is pivotally secured to the block 4 whereby it is adapted to move according to the movements of this block. The rod 17 can move parallel to its axis in the elongated slot 23 directed along a radius of the box 12. This motion is controlled by the knob 24.

The whole of the sight line having been thus briefly described I will now proceed to describe more in detail each of its parts and their manner of working.

Figs. 4 and 5 are explanatory diagrams which show how the box 12 is made to be raised and lowered with reference to the casing 6. The crank 13 provides for the rotation of a pinion 26 meshing with two racks 27, 28 disposed at right angles one with reference to the other. The rack 28 ends with a projection actuating a lever 29 on the pivoting axis of which is keyed a toothed sector 30 meshing with the toothed ring 31 which is thus caused to rotate. This ring 31 is provided with an inner helical

rack having a coarse pitch meshing with a corresponding toothwork provided on the sleeve 32 which can rotate round the box 12 but cannot move vertically with reference thereto. Thus it is evident that the rotation of the ring 31 causes the box 12 to be raised or lowered and consequently as the box 12 is secured to the socket 14, the shaft 16 and the rod 17, also causes the latter to be raised or lowered and consequently the back sight to be suitably moved.

The Figures 5 and 6 allow the manner of taking into account the variations of speed to be understood.

The rod 17 passes through a sleeve 34 secured to a carriage 35 inside which another carriage 36 is adapted to slide. This carriage 36 is provided with a cam-shaped aperture 37. The carriage 36 passes through a longitudinal slot provided in the rod 17. This rod shows a cotter 38 which passes through the carriage 36 and engages the aperture 37. Besides the inner carriage 36 shows two stops 39 between which is disposed an eccentric 40 the rotation of which is controlled by the knob 24. It is easy to understand which are the relative movements of these several parts. In view of taking into account the speed, the knob 24 is rotated whereby the rotation of the eccentric 40 makes the inner carriage 36 move longitudinally. Latter carriage by means of the cotter 38 draws along with it the rod 17 and thereby the outer carriage 35. The whole arrangement moves inside the elongated slot 23. The knob 41 of the lower end of the rod 17 moves in the elongated slot 42.

When the aircraft serving as a target moves downwards or upwards the gunner who actuates the directing shaft 16 must give it a certain incline. Let us suppose for instance he lowers it whereby he provides for the lowering of the rod 17. This latter rod is compelled to follow the longitudinal slot 37 during its downward movement because the carriage 35 remains stationary. Consequently the rod 17 and therewith the outer carriage 35 moves from left to right. The speed value is increased by a given quantity by the profile given to the cam shaped aperture 37. It can be seen that, in the case of an aircraft which moves downwards, the mere inclination of the shaft 16 provides for the automatic addition to the speed marked of a correction corresponding to the increase of the speed for a descending aircraft. If the aircraft ascends, the reverse movements are, of course, provided.

Obviously the relative movement of the two carriages (inner and outer carriages) can be obtained by a great number of other mechanical equivalents.

Thus in the form of execution shown on Figs. 7 and 8 the inner carriage 45 directly controlled by the eccentric 46 shows

a notch 47 which can be engaged by the bell crank 48 the axis 49 of which is pivotally secured to the walls 50 constituting the outer carriage. The other end of the lever 48 appears as a ball 50' inserted in a recess 51 provided in the rod 52 corresponding to rod 17 on Fig. 5.

It may be readily understood that if the knob 53 is actuated the carriage 45 will be moved and thereby the bell crank 48 which does not rotate makes the outer carriage 50 and consequently the rod 52 move. If the shaft 54 is raised or lowered in the case of a rising or descending aircraft, the rod 52 will actuate the ball 50' lodged in the recess 51. The ball will thus rise or descend and consequently the lever 48 will be urged round its axis 49; but as it bears against the notch 47 of the carriage 45 which remains stationary the axis 49 is made to move from right to left or from left to right. The axis 49 draws along with it the outer carriage 50 and therewith the rod 52. The required correction is thus automatically introduced.

It should be noted that in both above described forms of execution, it is generally of advantage, for the sake of simplicity in the handling of the apparatus, to limit the scale of speeds of the target to two values only. Thus the two values of 200 and 300 kms. per hour can be chosen. Under such conditions stop devices are provided which make the knobs be set in the two exact positions corresponding to these speeds. These stop devices can be constituted for instance as shown on Figs. 5 and 7 by a ball 56 urged by a spring 57. The ball 56 can enter one or the other of the recesses 58, 59 (Fig. 4) provided on the surface of the box 12. In a similar manner the scale of distances can be restricted to two values, for instance 600 and 1400 m. by providing two stops for the crank 13 which allow latter to be set in two accurate positions.

When the speeds are thus restricted to two values, the simplified form of execution shown on Figs. 9 and 10 can be used. In this form of execution there is only one carriage 60 provided with a rack 61 engaging a toothed sector 62 secured to the shaft 63 and moving consequently when the shaft 63 rotates round its pivot. Inside the carriage 60 is provided a perforation 64 through which passes the sleeve 65 provided with an eccentric bore 66 through which passes the rod 67. The sleeve 65 is provided with a knob 68 which can be given only two positions. It can be seen that if the knob 68 is rotated and given one of these two positions, the rod 67 will be given the position corresponding to one of the standard speeds chosen. On the other hand when the shaft 63 is raised or lowered, the carriage 60 is actuated by means of the sector 62 and the

rack 61 and thereby the correction due to the upward or downward movement of the aircraft is automatically made.

As explained hereinbefore with reference to Fig. 2, the second form of execution of the apparatus a general view of which is given on Fig. 11 provides for a constant length Oe equal to one. Therefore the block 70 wherein the rod 71 is adapted to slide is stationary with reference to the fire-arm 70 instead of moving along latter as in the first form of execution described with reference to Figs. 3 to 10 proportionately to the distance. The apparatus comprises as in the first case, a cylindrical casing 72 containing a box 73 which can be raised or lowered with reference to the casing 72 and rotate with reference thereto. The raising movement is produced by means of the toothed ring 74 controlled by a worm 75 secured to a rod 76 actuated by a milled knob 77. On the other hand the directing shaft serves like in the beforedescribed apparatus for controlling the position of the inner carriage.

The movement of the vertical rod 79 along a radius of the box 75 is produced by the inner carriage 82 the upward and downward movements of which are controlled by the toothed ring 83 outwardly controlled by the rack 84 to which are given the longitudinal movements proportional to $\frac{VT}{D}$. The carriage 82 controls the rod 79 by means of the inner toothwork of 82, a pinion 81 meshing therewith and a rack 80 secured to the rod and engaging the said pinion.

The movements of the rack 84 are controlled by the calculating box 85 (Fig. 11). The principle which is embodied in this calculating mechanism is a very simple triangulation principle diagrammatically illustrated on Fig. 12. If the right angled triangle pqr is considered wherein pq is a constant and qr is equal to $\frac{T}{D}$ and a length ps equal to V is measured along the side pq and a parallel st , to qr is drawn through the point s the following equality is obtained:

$$\frac{x}{ps} = \frac{qr}{pq} \quad 115$$

if x is supposed to indicate st ; this gives

$$\frac{x}{V} = \frac{T}{K} \quad 120$$

(K being a constant) or

$$x = \frac{VT}{D} = \frac{I}{K} \quad 125$$

Therefore x is save a constant factor, equal to the product $\frac{VT}{D}$.

The mechanism itself comprises a carriage 86 which is moved by the milled knob 87 so

as to make the index 88 mark the required value on the speed scale 89.

Perpendicularly to the direction of the movement of this carriage is disposed a rod 76 which is controlled by the knob 77 and which allows the accurate setting of the back-sight as explained hereinabove. This rod 76 which is threaded on part of its length bears a nut 90 which is adapted to move longitudinally along the rod. This nut is provided with a projection 91 which engages the groove 92 of a lever oscillating round a point 94 which is the origin of the vector representing the speeds and which corresponds to the point p of the triangle pqr in Fig. 12. The distance from point 94 to the rod 76 is constant. The point of the lever 93 moves in front of a graduation 95 whereon are marked the distances D , this graduation being such as will make the distance $91-96$ be equal to $\frac{VT}{D}$. It can be seen that the distance interferes twice in this arrangement once for the back sight and once for the correction due to the displacement of the aircraft and that it is necessary for this to actuate only one knob 77. The carriage 86 is provided with a groove 97 parallel to the rod 76 and disposed at the height of the index 88. The lever 93 is provided on the other hand with a slot 98 disposed along its axis. A finger 99 is adapted to pass through both slots and is secured besides to the slider 100 which can slide in the slot 101 provided in the bent end of the rack 84. It can be seen that the finger 99 will be constantly held at the intersection of the slot 101 and of the slot 97. By means of the slider it thus causes the rack 84 to move as required proportionately to $\frac{VT}{D}$.

What I claim is:

1. Sight-line for fire-arms adapted to fire against movable aerial targets comprising a constantly vertical cylindrical casing secured to the firearm, a cylindrical box disposed inside said casing, means for rotating and for moving longitudinally said box with reference to the casing, a projection on said casing, a directing shaft pivotally secured to said projection and adapted to be directed parallel to the path of the aerial target, a vertical shaft passing through the cylindrical box connected with the directing shaft, and adapted to move along a radius of the box, a connecting rod linked with last mentioned vertical shaft and with a point of the fire arm and aiming means secured to said connecting rod.
2. Sight line for fire-arms adapted to fire against movable aerial targets comprising a support secured to the fire arm, a cylindrical casing secured after the manner of a pendulum to said support, a cylindrical box disposed inside said casing, means for rotating

and for moving longitudinally said box with reference to the casing, a projection on said casing, a directing shaft pivotally secured to said projection and adapted to be directed parallel to the path of the aerial target, a vertical shaft passing through the cylindrical box connected with the directing shaft, and adapted to move along a radius of the box, a connecting rod linked with last mentioned vertical shaft and with a point of the fire arm, aiming means secured to said connecting rod and a second connecting rod parallel to the first rod secured to the vertical shaft and to a point of the fire-arm.

3. Sight-line for fire-arms adapted to fire against movable aerial targets comprising a support secured to the fire arm, a cylindrical casing secured after the manner of a pendulum to said support, a cylindrical box disposed inside said casing, means for rotating and for moving longitudinally said box with reference to the casing, a projection on said casing, a directing shaft pivotally secured to said projection and adapted to be directed parallel to the path of the aerial target, a vertical shaft passing through the cylindrical box connected with the directing shaft, and adapted to move along a radius of the box, a connecting rod linked with last mentioned vertical shaft and with a point of the fire arm, aiming means secured to said connecting rod and a second connecting rod parallel to the first rod secured to the vertical shaft and to a point of the fire-arm.

4. Sight-line for fire-arms adapted to fire against movable aerial targets comprising a support secured to the fire arm, a cylindrical casing secured after the manner of a pendulum to said support, a cylindrical box disposed inside said casing, means for rotating and for moving longitudinally said box with reference to the casing, a projection on said casing, a directing shaft pivotally secured to said projection and adapted to be directed parallel to the path of the aerial target, a vertical shaft passing through the cylindrical box connected with the directing shaft, and adapted to move along a radius of the box, a connecting rod linked with last mentioned vertical shaft and with a point of the fire arm, aiming means secured to said connecting rod and a second connecting rod parallel to the first rod secured to the vertical shaft and to a point of the fire-arm, a socket surrounding the vertical shaft, a movable carriage surrounding same, a second carriage sliding inside said movable carriage, means for moving said second carriage proportionately to the speed of the aerial target, means whereby the movements of said

second carriage control those of the first carriage and of the cylindrical box, the first carriage being moreover independently controlled by the rotation of the directing shaft.

5. Sight-line for fire-arms adapted to fire against movable aerial targets comprising a constantly vertical cylindrical casing secured to the fire-arms, a cylindrical box disposed inside said casing, means for rotating and 10 for moving longitudinally said box with reference to the casing, a projection on said casing, a directing shaft pivotally secured to said projection and adapted to be directed parallel to the path of the aerial target, a 15 vertical shaft passing through the cylindrical box connected with the directing shaft, and adapted to move along a radius of the box, a connecting rod linked with lastmentioned vertical shaft and with an adjustable 20 point of the fire arm and aiming means secured to said connecting rod, means whereby the distance of the vertical shaft to the axis of the vertical casing is proportional to the speed of the target and a part providing simultaneously for a vertical movement of the 25 box with reference to the casing which is adapted to give the back sight correction and for the movement of the adjustable connection of the connecting rod along the fire arm, both movements being proportional to the distance D.

6. Sight-line for fire-arms adapted to fire against movable aerial targets comprising a constantly vertical cylindrical casing secured to the fire arm, a cylindrical box disposed inside said casing, means for rotating and for moving longitudinally said box with reference to the casing, a projection on said casing, a directing shaft pivotally secured to said projection and adapted to be directed parallel to the path of the aerial target, a vertical shaft passing through the cylindrical box connected with the directing shaft, and adapted 40 to move along a radius of the box, a connecting rod linked with lastmentioned vertical shaft and with a stationary point of the fire arm and aiming means secured to

said connecting rod, and a calculating mechanism providing for said vertical shaft to 50 move along a radius of the casing and for the distance thereof to the axis of the casing to be proportional to $\frac{VT}{D}$.

7. A sight line as claimed in claim 6 55 wherein the calculating mechanism comprises a carriage the movements of which are proportional to V, a slider adapted to move perpendicularly to the movement of the carriage and the movements of which are 60 proportional to $\frac{T}{D}$, a slotted lever connecting the slider to the zero of a speed scale, a slot provided in the carriage and parallel 65 to the movements of the slider, a finger engaging this slot and the slot in the lever whereby it is moved by a distance proportional to $\frac{VT}{D}$ and means whereby the move- 70 ments of the finger are transmitted to the vertical shaft.

8. A sight line as claimed in claim 7 75 wherein the calculating mechanism comprises a carriage the movements of which are proportional to V, a slider adapted to move perpendicularly to the movement of the carriage and the movements of which are

proportional to $\frac{T}{D}$, a slotted lever connecting 80 the slider to the zero of a speed scale, a slot provided in the carriage and parallel to the movements of the slider, a finger engaging this slot and the slot in the lever 85 whereby it is moved by a distance proportional to $\frac{VT}{D}$ and means whereby the movements of the finger are transmitted to the vertical shaft and a part controlling simultaneously the slider and the back sight.

In testimony whereof I affix my signature.

YVES PAUL GASTON LE PRIEUR.
